Carl E. Anderson, Kansas City, Kans.

Application September 11, 1944, Serial No. 115,261

Term of patent 14 years

(Cl. D80—9)

To all whom it may concern:

Be it known that I, Carl E. Anderson, a citizen of the United States, residing at Kansas City, in the county of Wyandotte and State of Kansas, have invented a new, original, and ornamental Design for a Carpet Display Rack, of which the following is a specification, reference being had to the accompanying drawing, forming a part thereof.

Fig. 1 is a perspective view of the carpet display rack showing my design.

Fig. 2 is a front elevational view thereof; and Fig. 3 is an end elevational view thereof.

I claim:

The ornamental design for a carpet display rack, as shown.

CARL E. ANDERSON.
